LISAF G. AJAMIAN AND YERVANT E. AJAMIAN, OF WEST HOBOKEN, NEW JERSEY.

SANITARY URINE TUBE FOR INFANTS.

Application filed June 6, 1923. Serial No. 443,734.

To all whom it may concern:

Be it known that we, LISAF G. AJAMIAN and YERVANT E. AJAMIAN, citizens of the United States, and residents of West Hoboken, in the county of Hudson and State of New Jersey, have invented a new and Improved Sanitary Urine Tube for Infants, of which the following is a full, clear, and exact description.

10 This invention relates to a sanitary urine tube or receptacle for use in connection with infants or adults.

An object of the invention is to provide a sanitary, removable, easily cleansed receptacle which can be readily attached to and removed from the person of the wearer for the reception of liquid, especially in the case of male persons.

Another object concerns the provision of means whereby this receptacle can be very easily kept in a clean, sanitary condition, and is constructed to be as unobtrusive as possible.

A further object concerns the provision of means whereby the use of this article causes a minimum of confusion and irritation.

The invention is illustrated in the drawings, of which—

Figure 1 is a perspective view of the device;

Fig. 2 is a section taken on the line 2—2 of Fig. 1, showing in dot-and-dash lines the relation of the human figure to the device in use;

35 Fig. 3 is a section taken on the line 3—3 of Fig. 1;

Fig. 4 is a section taken on the line 4—4 of Fig. 2;

40 Fig. 5 is a section taken on the line 5—5 of Fig. 2; and

Fig. 6 is a section on the lower end of the tubular part of the device showing a modified form thereof.

The form of the invention shown in the drawings is a preferred form, although it is understood that modifications in the construction and arrangement of the parts and in the character of the materials used may be adopted without departing from the spirit of the invention.

In handling infants and certain types of adults, especially invalids, it is often found that discharges of liquid therefrom are not easily controllable, and for that reason it is highly necessary to provide some means

to receive such liquids, which device can be attached to the person of the wearer, can be readily removed, and can be easily cleaned and kept in a sanitary condition.

To this end I provide a tubular member, 60 preferably made of some waterproof material, attached to the body of the wearer and at its lower end so folded and held together by suitable fastening means as to be liquid tight but capable, when the fastening 65 means is unfastened, of being opened to remove the discharge of liquid therefrom. Near the upper end of this tubular member or receptacle is a valve arrangement or auxiliary chamber constructed to permit the 70 flow of liquid therethrough in one direction but not in the reverse direction. Into this auxiliary chamber the genital organ of male persons projects, so that any discharge 75 therefrom will be properly received. This tubular member or receptacle is attached to a body portion of suitable material, such as linen, although it may be made of stiffer material, such as heavy rubber or waterproof fabric; and this sheet of material or 80 support acts also to lie against the genital organs to support them. The support is attached to the body of the wearer by being connected at one end to a belt or strip passing around the waist, and at the other end 85 by strips passing beneath the groin.

As shown particularly in the figures, the apparatus includes a belt 1 adapted to pass around the waist, and two strips 2 and 3 adapted to pass beneath the legs of the 90 wearer underneath the groin. The ends of these strips 2 and 3 are connected by suitable snap fasteners to one end of a sheet 4 to act as a support for certain of the genital organs, preferably male persons. The other 95 end of this sheet or support is connected by snap fasteners to the front of the belt 1. This sheet or support is provided with an aperture 5 to which one end of a tubular member or receptacle 6 is fastened in any suitable manner, such as by sewing. This tubular member or receptacle at its lower end is folded, as shown in Figs. 2 and 5, and when folded is held in this condition by snap fasteners such as 7 and 8 so that when 100 folded the lower end is sufficiently tight to prohibit the outflow of liquid from the receptacle. When, however, these fasteners are unfastened and the folds are shaken out, the lower end of the tubular receptacle is 110

entirely open, permitting the liquid to pass out. The material of which this tubular member is made is, of course, no part of the invention except that it should preferably be 5 of some waterproof material like rubber or waterproof linen. In the upper end of the receptacle is an auxiliary chamber 9, also formed of waterproof material, fastened at its upper end to the upper end of the receptacle 6, but at its lower end hanging over within said receptacle. This lower end is preferably drawn together at its edges so that liquid discharged within this auxiliary receptacle will pass out thereof into the 15 main receptacle 6 but will not have a tendency or be able to pass back. This auxiliary receptacle or chamber 9 is preferably lined with some soft material 10, which may preferably be cotton or linen, because into this auxiliary receptacle there projects one of the 20 genital organs and irritation of this organ is not desirable, and for this reason the soft lining is provided.

As shown in Fig. 6, the bottom of the main receptacle may be provided with a suitable metallic discharge plug 11 which can be closed by an ordinary stopper 12 of any suitable design.

It will, therefore, be seen that I have provided a simple, efficient device which can be used to avoid unnecessary and embarrassing conditions due to faulty control of urine flow, which is, nevertheless, something that can be worn unobtrusively and is easily removed from the body and can be easily kept clean at all times.

What we claim is:

1. A sanitary receptacle which includes a tubular waterproof receptacle having a normally open bottom provided with a plurality of folds, a fastening means attached thereto to hold the lower folded end closed when said end is folded, an auxiliary receptacle or chamber at the other end of said main receptacle adapted to receive a male genital organ, and a valve in the lower end of said auxiliary receptacle permitting the flow of liquid therethrough in one direction only.

2. A sanitary receptacle which includes a tubular waterproof receptacle having a nor-

mally open bottom provided with a plurality of folds, a fastening means attached thereto to hold the lower folded end closed when said end is folded, an auxiliary receptacle or chamber at the other end of said main receptacle adapted to receive a male genital organ, a valve in the lower end of said auxiliary receptacle permitting the flow of liquid therethrough in one direction only, and lining of soft non-irritating material 60 for said auxiliary chamber or receptacle.

3. A sanitary receptacle which includes a tubular waterproof receptacle having a normally open bottom provided with a plurality of folds, a fastening means attached thereto to hold the lower folded end closed when said end is folded, an auxiliary receptacle or chamber at the other end of said main receptacle adapted to receive a male genital organ, a valve in the lower end of said auxiliary receptacle permitting the flow of liquid therethrough in one direction only, 65 a supporting sheet to which the upper end of said tubular member is fastened, and a waistband to which one portion of said supporting sheet is fastened.

4. A sanitary receptacle which includes a tubular waterproof receptacle having a normally open bottom provided with a plurality of folds, a fastening means attached thereto to hold the lower folded end closed when said end is folded, an auxiliary receptacle or chamber at the other end of said main receptacle adapted to receive a male genital organ, a valve in the lower end of said auxiliary receptacle permitting the flow of liquid therethrough in one direction only, 70 a supporting sheet to which the upper end of said tubular member is fastened, and a waistband to which one portion of said supporting sheet is fastened, 75 and a strip member connected to the waistband passing between the groin and connected to the other end of said supporting sheet.
